Primary Examiner — Dana K Weiland*Assistant Examiner* — Messina L Smith(74) *Attorney, Agent, or Firm* — Berger Singerman LLP; Geoffrey Lottenberg(57) **CLAIM**

The ornamental design for an electronic grinder, as shown and described.

DESCRIPTION

FIG. 1 is a perspective view of an electronic grinder, showing the new design;

FIG. 2 is a front side elevation view of the electronic grinder;

FIG. 3 is a rear side elevation view of the electronic grinder;

FIG. 4 is a left elevation view of the electronic grinder;

FIG. 5 is a right elevation view of the electronic grinder;

FIG. 6 is a top elevation view of the electronic grinder; and,

FIG. 7 is a bottom elevation view of the electronic grinder.

1 Claim, 7 Drawing Sheets(56)
